UNITED STATES PATENT OFFICE.

AUGUST L. SCHULTZ, OF CLEVELAND, OHIO, ASSIGNOR TO THE AMERICAN MULTIGRAPH COMPANY, OF CLEVELAND, OHIO, A CORPORATION OF OHIO.

ADDRESSING MACHINE.

Application filed June 14, 1926. Serial No. 115,818.

This invention relates to a rotary machine for printing addresses, as for instance addressing envelopes. The object of the invention is to provide a very simple mechanism for causing revolution at proper time and speed of a platen adapted to coact with an address plate held on a suitable drum.

My mechanism is designed to cause a platen, much smaller than the drum, to coact with the drum once only on each rotation of the drum and when in coaction to have the same peripheral speed as the drum, and to accomplish this by a very simple arrangement of mechanism. Such mechanism is hereinafter more fully described in connection with the drawings which illustrate a preferred embodiment of my invention.

In the drawings, Fig. 1 is a plan; Fig. 2 is a vertical cross-section on the line 2—2 of Fig. 1; Fig. 3 is a vertical cross-section on the line 3—3 of Fig. 1, looking in the opposite direction from Fig. 2; Fig. 4 is a fragmentary elevation of the platen controlling mechanism, showing the platen gear one revolution different from the showing in Fig. 3; Fig. 5 is a longitudinal vertical section through the machine; Fig. 6 is a section through the platen shaft in an approximately vertical plane, as indicated by the line 6—6 in Fig. 3.

As shown in the drawings, the machine is adapted to carry not only a changeable address plate, but a body form to print addressed circular letters, there being one platen coacting with both the body form and address to print the letter and another platen coacting with the address only to address the envelope. This invention is concerned with this latter platen.

The printing machine proper is of the general type of the Multigraph and comprises a rotary drum 10 mounted on a shaft 11, journalled in end frame plates 12 and 13 above a roller platen 14 mounted on a shaft 15. Gearing 16 and 17 and an Oldham coupling 18 connect the drum and this platen. Any suitable means, as for example a crank 19, is provided for rotating the drum and platen.

The sheets to be printed may be fed to such machine automatically or manually as desired. I have indicated in Fig. 3 at 20 a pair of coactable rolls to control the paper fed, the roll 21 being connected by a gearing 22 with the platen gear 16. I have also in-

dicated at 25, a paper ejecting roll connected by gearing 26 with the platen gear 16.

I have shown mounted on the drum a means for printing the body of a letter comprising a blanket 30 stretched about a segmental portion of the drum and having raised overhanging projections 32 carrying embossed printing strips 33, Fig. 1. An inking ribbon 35 is provided, adapted to overlie the printing form, such ribbon being mounted at its ends on spools 37 and 38 which are mounted in the drum.

It will be seen that in the construction described, when the drum is rotated, as by means of the crank or otherwise, paper fed between the drum and platen 14 is printed by the type characters through the ribbon.

The body of the drum adjacent one edge of the segment is shown in Fig. 2 as provided with a pair of longitudinal channels 40, 41 for the reception of the address plate 42. This plate may be of the form shown, having an arcuate intermediate region and depressed edge portions under-curved on themselves for strength, and adapted to occupy the channels 40 and 41 when it is shoved endwise into place. Between these channels is a portion of the drum providing a support for the intermediate portion of the plate. The plate, which is shown conventionally may if desired have raised projections like the blanket and carry similar embossed printing strips. The address plates may be inserted manually or in other manner as desired during a temporary cessation of the rotation of the drum thus giving a different plate for each rotation.

The mechanism described enables the simultaneous printing of the body and address of an addressed letter through an inking ribbon with comparative rapidity. Mechanism which I will now describe is provided to enable the envelope to be printed from the same address plate while in its position on the drum.

The envelope platen has a segmental portion, the arcuate extent of which corresponds with that of the address plate, and the mechanism sets such platen into motion at the proper time and at the proper speed so that it will coact with the address plate on the drum.

The segmental portion 50 of the envelope platen is rigidly mounted on a roller 51, being shown as secured thereto as by screws 110

52. This roller is rotatable on a shaft 53 which is eccentrically mounted so as to be adjustable. The shaft is shown as having an eccentric extension 54 at one end which is 5 mounted in a stationary tubular bearing 55 carried by the frame plate 12. At the other end the shaft is mounted in a suitable bearing in the frame plate 13. A small lever 57 on this end of the shaft enables its partial 10 rotation to adjust the platen, and the locking of this lever to the frame plate holds the platen in adjusted position.

Mounted on the exterior of the bearing 55 is a driven gear 60, meshing with the 15 drum gear 17. Adjacent this driven gear is a disk 61 adapted under certain conditions to be driven by this gear. This disk is connected by an Oldham coupling with the platen roller 51. As shown the disk is connected by pins 64 to a coupling member 65 which has diametric notches embracing projections on a floating member 66; projection set 90° ahead on the other side of this member engage notches in the platen roller.

25 The gear 60 has a pitch diameter which is an aliquot part of the pitch diameter of the drum gear 17. As shown the diameter gear 60 is one-half that of the drum gear, so that the gear 60 makes two rotations for every 30 rotation of the drum.

Pivoted on the side of the gear 60 is a pawl 62, the tail of which is pressed outwardly by a spring 63 carried by the gear so that the hooked nose 65 of the pawl is 35 pressed inwardly to bear against the edge of the disk 61. This disk is provided with a shoulder 67 which the nose of the pawl may engage. When in such engagement, the disk 61 revolves with the gear 60 and in 40 that case the platen roller and the segmental platen revolve simultaneously with the drum and at the same peripheral speed. To cause the platen 50 to coact with the printing drum for only one rotation of the latter, though 45 the platen gear 60 makes two rotations, I provide a throwout for the pawl 62, which, in the embodiment shown, acts on every alternate rotation of the platen gear and is effective for one rotation.

50 The mechanism just referred to comprises a cam 80 on a pinion 81 which meshes with the gear 60. This cam and pinion structure is journaled on a pin 82 carried by the frame plate 12. The pitch circle of the pinion 81 55 bears a non-aliquot relation to that of the gear 60, so that on one rotation of the gear 60 the cam 80 may come into position to coact with a shoulder 69 on the tail of the pawl 62, while on the next rotation this cam 60 is extended away from the pawl and hence idle. In the particular embodiment shown, this is effected by making the pinion of such diameter that the diameter of the pitch circle of the gear 60 is four and one-half times that 65 of the pinion.

It results from the construction described that if the parts are in the position shown in Fig. 3, the gear 60 will be connected with the disk 61 and thus the envelope platen is given one revolution during a one-half revolution of the printing drum. At the end of such revolution of the platen, the cam 80 reaches the lower region of its course, as indicated in Fig. 4, and there engages the shoulder 69 on the tail of the pawl and 70 withdraws the nose of the pawl from the notch 67. This frees the gear from the platen, and hence the next rotation of the gear is idle, and the platen remains stationary, the pawl nose tracking over the periphery of the disk 61. At the completion of that rotation the pawl nose will again swing into engagement with the notch 67, the cam 80 being at that time distant from the tail 75 of the pawl.

It will accordingly be seen that by the very simple arrangement of the gearing the cam and the pawl I am able to cause the platen on a comparatively small roller to rotate at the same number of rotations with 80 the comparatively large drum and at the same time at the same peripheral speed.

I have spoken of the gear ratio of the pinion 81 and the gear 60 as being one to four and one-half. However, this ratio may 85 be made of any whole number plus a fraction which is dependant on the ratio of the platen gear and the drum gear. In other words, the number of rotations of the cam for each rotation of the platen gear is any 90 number, plus a fraction, the numerator of which is unity and the denominator of which is the quotient obtained by dividing the pitch diameter of the gear on the Multigraph drum by the pitch diameter of the gear on the platen. Thus, if the Multigraph gear is twice the diameter of the platen gear, the fraction of a rotation of the cam for each rotation of the platen gear is one-half. If the Multigraph gear were three times 95 the diameter of the platen gear, such fraction of a rotation of the cam would be one-third that of the platen gear, in which case, the cam would extend for two-thirds of a circle and the pawl would be released on 100 only every third rotation of the platen gear. In any case the number of rotations of the cam may be expressed as an improper fractional multiple of those of the platen gear.

In order to stop the revolution of the envelope platen immediately, when the pawl is disconnected from the disk 61, I provide a constantly acting friction brake. The drag thus caused is immaterial when the platen is being driven, but when the platen 105 is released is sufficient to stop it at once. I have shown this brake consists of a leather disk 90 mounted on a plate 91 and pressed by springs 92 into contact with the end of 110 the platen roller 51.

As heretofore stated the address plate may be installed on the drum and removed therefrom manually or otherwise as desired. For simplicity I prefer to perform this operation manually, there being a temporary pause between rotations sufficient to accomplish it. As indicated in Figs. 1 and 5, there is an abutment 100 pressed outwardly by a spring 101 and tending to discharge the plate 42, a latch 103 is adapted to hold it in place against the spring action. The plate may be simply shoved manually lengthwise of the drum toward the crank, beneath a bridge 105 supporting the edge of the ribbon, until the plate passes the latch, which will then spring out to hold it. At the end of the rotation, a depression of this latch will allow the spring 101 to act to eject the plate to a point where it may be grasped by the operator. Reference may be made to a pending application of John A. Hult, No. 100,224 for a fuller description of the installation and removal of the plate.

Assuming that a fresh plate is installed on the drum for each rotation, it will be seen that paper fed between the controlling feed rollers may be printed between the drum and platen 14 to produce addressed circular letters, and while the body of the letter is being printed, the address plate which has coacted with the platen 14 may coact with the segmental platen 50 to print the address on an envelope. Such envelope will be carried upwardly by the coaction of the segmental platen and the address plate and be suitably discharged.

I have shown in Figs. 1 and 2, a suitable pocket for receiving a blank envelope and holding it in position for printing. This pocket comprises a pair of separated shield plates 110 and 111 depending between the drum and the roller 51 and connected at the bottom by a cross bar 113 which is adapted to support the envelope in proper position. The two plates have openings 115, 116 through them, through which the segmental platen acts. The plate 110 is shown as having a rearward projection 11^a near its upper end to direct the envelope being discharged rearwardly, while the plate 111 curves over the platen roller 51 and forms a discharge shield. With such embodiment the envelopes may be readily inserted manually in the pocket one at a time and at the proper time each envelope is printed and discharged at the rear of the machine and may fall on the printed addressed letter bearing the corresponding address, unless it is desired to provide separate receptacles for the letters and envelopes.

Having thus described my invention, I claim:—

1. In a machine of the character described, the combination of a rotary printing member, a revoluble platen member, a rotary

driver, means for coupling said driver to said member including a movable periodically acting cam and a member which it engages less frequently than every rotation of the driver, and mechanism for changing the relation of said cam to the printing member while the machine is operating, the printing member and platen being in the same relative position at each period of engagement of the cam.

2. In a machine of the character described, the combination of a rotary printing member, a revoluble platen, a member adapted to travel concurrently with the printing member, means for locking said member to the platen when the platen is in a definite location with reference to the printing member and a periodically acting device movable with reference to the printing member to release said lock on one rotation of the other member and not on another rotation.

3. The combination of a rotary printing member, another member adapted to travel concurrently therewith, a platen adapted to coact with the printing member, means for locking said platen to said other member when the platen is in a definite location with reference to the printing member, a rotary cam and means whereby it may release said lock, said cam being active on one rotation of said other member and inactive on another rotation.

4. The combination of a rotary printing member, another member geared therewith, a platen adapted to coact with the printing member, means for locking said platen to said other member when the platen is in a definite location with reference to the printing member, a rotary cam and means whereby it may release said lock, said cam being active on one rotation thereof and inactive on another rotation.

5. The combination of a rotary printing member, a segmental platen, a rotary cam geared with the printing member, the rotations of said cam being an improper fractional multiple of those of said member whereby the cam is adapted to release the lock on certain rotations only of the member.

6. The combination of a rotary printing member, a segmental platen, a gear geared with the printing member, a lock for locking said gear to the platen, and a cam adapted to control said lock and geared with said gear, the rotations of said cam being an improper fractional multiple of those of the gear.

7. The combination of a rotary printing member having a gear, a second gear meshing therewith and having a pitch diameter which is an aliquot part of the pitch diameter of the printing member gear, a platen, a lock for connecting it to said gear, a pinion

connected with said gear and adapted to control the lock and having rotations which are a fractional multiple of that of the gear, said pinion carrying a cam adapted to periodically release said lock.

8. The combination of a rotary printing drum, having a gear, a second gear connected with the gear on the drum and having a pitch diameter which is an aliquot part of the 10 pitch diameter of the drum, a pinion geared with the drum, the pitch diameter of the second gear comprising a multiple of that of the pinion plus a fraction the numerator of which is unity and the denominator 15 of which is the quotient obtained by dividing the diameter of the drum by the diameter of said second gear.

9. In a machine of the character described, the combination of a printing drum having 20 a gear, a second gear meshing therewith, a pinion geared with the second gear, a cam on the pinion, a pawl on the second gear operated by the cam, a platen, and means whereby the pawl may connect the platen to the 25 second gear, the ratio of the gear on the drum, the second gear and the pinion being such that the number of rotations of the cam for each rotation of the second gear is a number plus a fraction, the numerator of 30 which is unity and the denominator of which is the quotient obtained by dividing the pitch diameter of the gear on the drum by the pitch diameter of the second gear.

10. The combination of a rotary drum, 35 means for carrying thereon a removable address plate, a segmental platen adapted to revolve in coaction with said address plate, gearing connecting said segmental platen with the drum and comprising a member 40 adapted to make a plurality of rotations for each rotation of the drum, a lock for connecting said member to the platen, and means for releasing said lock on certain 45 rotations of said member and coupling it on other rotations, comprising a rotary cam movable with reference to the drum and so geared that its rotations are a fractional multiple of those of said member, whereby the platen may make one rotation for each 50 rotation of the printing member and at the same peripheral speed.

11. The combination of a rotary drum, 55 means whereby a removable address plate may be mounted thereon, said address plate being changeable for successive rotations, a platen adapted to coact with said address plate, a gear for rotating said platen, meshing with a gear on the drum, a lock for connecting said gear with the platen, a movable cam for controlling said lock, and a 60 third gear connecting said cam with the platen gear.

12. The combination of a rotary drum, 65 longitudinal channels therein in which an address plate may be mounted, said drum

being provided with a gear, a second gear meshing with the gear on the drum, a segmental platen adapted to coact with the address plate, said segmental platen being substantially coaxial with said second gear, a 70 pawl adapted to connect the second gear with the platen, a rotary cam adapted to make a plurality of rotations for each rotation of the drum and to act on the pawl to disconnect it and means whereby said cam 75 acts on the pawl on one rotation of the second gear and misses such action on another rotation of the second gear.

13. The combination of a rotary printing member, a gear geared therewith, a platen coaxial with said gear, a notched disk rotatable with the platen, a pawl pivoted on the gear and having a nose adapted to engage the notch of the disk, a spring for retaining such engagement, a cam adapted to act on the pawl to withdraw the nose from the pawl on the disk, said cam being rotatable, a plurality of times for each rotation of the printing member and having a non-aliquot 90 gear ratio to the platen gear.

14. The combination of a rotary printing drum, means thereon for carrying a body-form to be printed, means for carrying a changeable address form, a platen adapted to coact with both forms, a second platen adapted to coact with the address form only while in position on the drum, said second platen being segmental, a member mounted substantially coaxially with the second 100 platen and geared with the drum, a pawl adapted to connect said member with the platen, a rotary cam adapted to make a plurality of rotations for each rotation of the drum and to swing said pawl out of such engagement to enable the member to rotate independently of the platen, and means whereby the rotations of the cam and member have a non-aliquot ratio.

15. The combination of a rotary printing drum, means thereon for carrying a body-form to be printed, means for carrying a changeable address form, a platen adapted to coact with both forms, a second platen adapted to coact with the address form only while in position on the drum, said second platen being segmental, a gear mounted substantially coaxially with the second platen and meshing with a gear on the drum, a pawl carried by said platen gear and adapted to coact with a notched disk on the platen, a cam adapted to swing said pawl out of such engagement to enable the second gear to rotate independently of the platen, and a pinion carrying the pawl and meshing with said second gear, said second gear and pinion having a non-aliquot gear ratio.

16. The combination of a pair of coactable rotary members of different diameters, a rotary driver for the smaller member geared with the larger member to make a plurality 130

of rotations for each rotation of the larger member, and mechanism for locking the smaller member to its driver once for each rotation of the larger member, said mechanism including means which makes a plurality of rotations for each rotation of the larger member, but acts on the driver only once for each rotation of the larger member.

17. In a machine of the character described, the combination of a rotary printing member, a revoluble platen member and rotary driver therefor, said driver being geared with the printing member to make a

plurality of rotations for each rotation of the printing member, said mechanism including a clutching member driven by the driver and a rotary controlling device which makes a plurality of rotations for each rotation of the printing member, but acts on said clutching member only once for each rotation of the printing member and while the printing member is in the same position for each rotation.

In testimony whereof, I hereunto affix my signature.

AUGUST L. SCHULTZ.
